UNITED STATES PATENT OFFICE.

PATRICK FRANCIS DENNING, OF CLEVELAND, OHIO.

INDIVIDUAL-TOWEL HOLDER.

1,298,910.

Specification of Letters Patent. Patented Apr. 1, 1919.

Application filed May 1, 1917. Serial No. 165,690.

To all whom it may concern:

Be it known that I, PATRICK F. DENNING, a citizen of the United States, residing at Cleveland, in the county of Cuyahoga and State of Ohio, have invented a new and useful Individual-Towel Holder, of which the following is a specification.

This invention relates to individual towel holders.

10 The object is to provide a device having means for holding an individual towel or other article, such as a hat or coat, and at the same time to embody means for displaying the name or number of the user or owner of 15 the article held thereby, the name-displaying means being combined with the holding means in a unitary structure, and so arranged as to permit of the ready substitution of one name or number for another at 20 any time, upon a simple manipulation of the parts.

The device of the present application is designed as an improvement upon the structure shown, described and claimed in Patent 25 No. 818,421, issued to me April 24, 1906, the principal feature of improvement in the present device residing in the name or number displaying means and its interchangeability.

30 A full and complete understanding of the invention may be obtained from a consideration of the following detailed description, taken in connection with the accompanying drawing forming a part of this specification; it being understood that while the drawing shows a practical form of the invention, the latter is not confined to strict conformity therewith, but may be changed or modified, so long as such changes or 35 modifications mark no material departure from the salient features of the invention, as specifically pointed out in the appended claims.

In the drawing in which like reference characters designate similar parts throughout the several figures:

40 Figure 1 is a front elevation of a combined holding device and detachable name plate therefor, constructed in accordance with the present invention.

45 Fig. 2 is a rear elevation thereof.

Fig. 3 is a vertical longitudinal sectional view of the same.

50 Fig. 4 is an enlarged detail rear elevation

of the upper portion of the device, illustrating the method of actuating the locking means for the name plate. 55

Fig. 5 is a detail perspective view of the detachable name plate frame.

Fig. 6 is a detail perspective view of the locking bolt therefor.

Fig. 7 is a detail front elevation of the upper portion of the shell or casing, with the name plate frame removed therefrom.

Referring to the drawing, there is shown 65 a hollow metallic shell or casing 1 formed of suitable sheet metal, and conforming substantially to that shown in the hereinbefore mentioned patent. In the present instance, however, the sides of the housing portion of 70 the casing are laterally flared and enlarged, as indicated at 2, to provide a cavity or recess at the upper portion of the shell or casing 1, for the double purpose of providing ample interior space for the accommodation 75 of locking means to be described, and for the support of designating means, such as a name plate, number, etc., as will hereinafter appear.

The lower or narrow portion of the shell 80 or casing 1 is suitably constructed to have mounted therein article holding means, such as shown in the said patent, and permits of the proper operation of the holding member 3 when actuated by the projecting button 4, 85 said parts being arranged in a vertical position, and since this mechanism forms no part of the present invention, no further attempt to describe the same will be made.

At the top of the flared portion 2 of the shell or casing 1, the side walls 5 are continued vertically and in parallelism, and are joined at the top by an inclined wall 6, which constitutes, in effect, a relatively wide platform for the support of a name card 7 or other device for designating the owner or user of the towel, garment or other article to be held. Spaced aligned slots 8 are formed in the inclined upper wall 6 adjacent to the top edge thereof, the said wall terminating 100 along its upper edge in an attaching flange 9, suitably apertured for the reception of one or more fastening devices, as appears in Fig. 3 of the drawing. The slots 8 are arranged adjacent to the end walls 5 and constitute 105 means for assisting in retaining in position a card holding frame 10.

At the point of intersection of the inclined

top wall 6 with the front wall of the shell or casing 1, and at the center of the same, another and larger slot 11 is provided through which is adapted to pass a portion of the 5 card holding frame 10 about to be described. The frame 10 is preferably stamped of suitable sheet metal, and includes a surrounding flange 12, 12^a, 12^b, which, when the device is applied to the inclined platform 10 form 6, provides ample space beneath the same for the reception of the card 7, and an overlying strip 13 of transparent material, preferably celluloid or isinglass, which protects the card from becoming damaged. 15 The flange 12 at the top of the frame is narrow, the flanges 12^a at each end are wide and embrace the side walls 5 of the casing, the flange 12^b at the bottom is inclined so as to fit flat upon the inclined platform. 20 The card holding frame 10 is provided with the usual sight opening 14 for exposing the name or number upon the card, and has formed upon the flange 12, along the upper side of the frame, spaced angular lugs or 25 extensions 15, which are adapted to enter into the aligned slots 8 of the inclined upper wall 6 of the casing 1, and when the frame 10 is brought to a resting position thereupon, to under-ride the said wall 6 at the upper 30 sides of the slots 8 and prevent the withdrawal of the frame 10 when the same is held against rocking movement. To prevent such rocking movement, the frame 10 is provided upon its front or lower depending 35 flange 12 with a centrally located inwardly directed keeper-tongue 16, which is adapted to pass through the centrally located slot 11 in the casing, and to normally lie in the path of movement of a spring actuated bolt 17, 40 which is suitably mounted upon the underside of the upper inclined wall 6 of the shell or casing 1.

The bolt 17, in the present device, is formed from a rectangular piece of sheet 45 metal having a struck up portion 18 constituting a lug, against the rear or upper side of which a metallic spring 19 is adapted to bear. Said spring is preferably formed from resilient spring wire of a length to be 50 housed between the end walls 5 of the upper enlarged portion of the casing, and to bear, at either side of the locking bolt 17, against the end members 20 of the guide or keeper 21, through which the sliding bolt 55 17 is adapted to reciprocate. The guide or keeper 21 is suitably apertured, as at 22, to permit the lug or projection 18 of the bolt 17 to pass therethrough, and to have sufficient movement to free the active end of the 60 bolt 17 from engagement with the keeper-tongue 16 of the frame 10, when the bolt is actuated in a manner to be described.

As shown in Fig. 4 of the drawing, one side wall 5 of the casing is provided with 65 an aperture 23, which is in alignment with

the downwardly extending lug or projection 18 of the sliding bolt 17, and is adapted to receive the end of a tool 24, nail, or other similar article, of sufficient length to reach the lug 18, when the same may be forced 70 backwardly against the pressure of the spring 19 sufficiently to withdraw the active end of the bolt 17 from its engagement with the keeper-tongue 16, as illustrated in dotted lines in Fig. 4 of the drawing. 75

As soon as the bolt is withdrawn from engagement with the keeper 16, the card holding frame may be lifted outwardly and the lugs 15 withdrawn from the slots 8 of the casing. In applying the card holding 80 frame, it is simply necessary to engage the said lugs with the slots and swing the card holding frame downwardly, when the keeper passing through the slot 11 strikes the projecting end of the bolt 11 and snaps into engagement therewith. 85

It will be noted that the card holding means is located at the top of the casing where it does not interfere with the operation of the article holding means, the latter 90 being arranged in a vertical plane while the card holding means is disposed in a horizontal plane.

From the foregoing, it will be seen that holding means for a towel, hat, coat, or other 95 article constructed in accordance with the provisions of the hereinbefore-mentioned patent has been combined in a single, self-contained structure, with detachable card or name plate holding means in a manner to 100 permit of the manufacture of the article at a low cost and that the said name plate, or other designating means is always in full view and may be readily changed in the manner described, while at the same time, 105 the said designating means is protected from dust, dirt, etc., and unauthorized persons are prevented from removing or changing the same. 110

What is claimed is:—

1. A single self-contained device for holding a towel, hat, coat or other article, having means for displaying in full view a card or name plate indicating the proprietorship of the article so held comprising a casing having article holding means mounted within the lower portion thereof, and having its side walls flared outwardly at their upper ends and connected by an inclined upper wall providing a relatively wide card supporting platform, which is disposed at the top of the casing beyond the range of the article holding means, a card-holding frame having a sight-opening to expose a card contained therein, and means for locking the card holding frame in position upon the platform. 115 120 125

2. A single self-contained device for holding a towel, hat, coat or other article, having means for displaying in full view a card or 130

- name plate indicating the proprietorship of the article so held comprising a casing having article holding means mounted in the lower portion thereof and having its side walls laterally flared at their upper ends and connected by an inclined upper wall providing a relatively wide card supporting platform which is disposed at the top of the casing above the article holding means, and
- 5 a card holding frame having a sight-opening to expose a card contained therein, said frame having end flanges to embrace the side walls of the casing, and locking means arranged within the casing for retaining the
- 10 a card holding frame having a sight-opening to expose a card contained therein, said frame having end flanges to embrace the side walls of the casing, and locking means arranged within the casing for retaining the
- 15 a card holding frame in an inclined position upon the said platform.
3. A single self-contained device for holding a towel, hat, coat or other article, having means for displaying in full view a card or
- 20 name plate indicating the proprietorship of the article so held comprising a hollow casing having means to secure it to a support, article holding means mounted within the casing and having an actuating member and
- 25 an active member projecting from the casing and arranged in an upright position, the side walls of the casing being flared and the casing widened out forming an enlarged portion at the top of the casing provided
- 30 with an inclined upper wall, constituting a card receiving platform which is located at right angles to the said actuating and active members and beyond their range of movement, an open frame adapted to expose the
- 35 name on a card to be placed upon the platform, said frame having flanged walls with its end flanges embracing the side walls of
- the casing, and means for retaining the said frame in position upon said platform.
4. A single self-contained device for holding a towel, hat, coat or other article, having means for displaying in full view a card or name plate indicating the proprietorship of the article so held, comprising a hollow casing having means to secure it to a wall or other support and having article holding means mounted in a vertical position in the lower portion thereof, said casing having its side walls laterally flared toward the top and having an inclined upper wall connecting the side walls and providing a relatively wide card receiving platform which is disposed in a plane at right angles to said article holding means, said platform being provided with spaced alined slots near its upper edge and a centrally-located slot at the lower edge thereof, a detachable card holding frame having a sight-opening for exposing a name-card to be placed upon the platform, said frame being provided with spaced angle tongues locking in said alined slots, and a central keeper-tongue entering said central slot, and a spring-pressed bolt mounted within the enlarged end of the casing beneath the platform and adapted to engage the keeper-tongue to retain the card frame in position.
- 55 In testimony, that I claim the foregoing as my own, I have hereto affixed my signature in the presence of two witnesses.
- 60 PATRICK FRANCIS DENNING.
